DESIGN FOR A WIND CONTROL WEATHER- PROOF FEED BOX OR SIMILAR ARTICLE

Carl Fenton, Arcadia, Fla.

Application March 7, 1945, Serial No. 118,307

Term of patent 14 years

(Cl. D12—2)

To all whom it may concern:

Be it known that I, Carl Fenton, a citizen of the United States, residing at Arcadia, in the county of De Soto and State of Florida, have invented a new, original, and ornamental Design for a Wind Control Weatherproof Feed Box or Similar Article, of which the following is a specification, reference being had to the accompanying drawings, forming part thereof.

Figure 1 is a front elevational view of a wind control weatherproof feed box or similar article, showing my new design.

Figure 2 is a rear elevational view,
Figure 3 is a top plan view,
Figure 4 is a side elevational view, and
Figure 5 is a horizontal sectional view taken on the line 5—5 of Figure 1.

I claim:

The ornamental design for a wind control weatherproof feed box or similar article, as shown.

CARL FENTON.
